(57) **CLAIM**

The ornamental design for a multi-slotted locator bushing, as shown and described.

DESCRIPTION

FIG. 1 provides a top right perspective view of a multi-slotted locator bushing.

FIG. 2 provides a right side view thereof.

FIG. 3 provides a left side view thereof.

FIG. 4 provides a front view thereof, the back view being the same as the right view.

FIG. 5 provides a top view thereof.

FIG. 6 provides a bottom view thereof; and,

FIG. 7 provides a bottom left perspective view thereof.

The broken lines shown in the drawings are included for the purpose of illustrating environmental structure and form no part of the claimed design.
